[57] CLAIM

The ornamental design for a modular telephone jack, as
shown and described.

DESCRIPTION

FIG. 1 is a top, front perspective view of a modular
telephone jack showing our new design;
FIG. 2 is a bottom, rear perspective view thereof;
FIG. 3 is a front, elevational view thereof;
FIG. 4 is a rear elevational view thereof;
FIG. 5 is a top plan view thereof;
FIG. 6 is a bottom plan view thereof;
FIG. 7 is a right side elevational view thereof;
FIG. 8 is a left-side elevational view thereof;
FIG. 9 is a bottom rear perspective view of a second
embodiment of our new design, the top, front, and op-
posite side of the second embodiment being identical to
those of the first embodiment.
